UNITED STATES PATENT OFFICE.

MAURICE TALEN AND GEORGE H. CROFT, OF GENESEO, ILLINOIS.

RIPPING ATTACHMENT FOR SEWING-MACHINES.

SPECIFICATION forming part of Letters Patent No. 603,931, dated May 10, 1898.

Application filed November 23, 1897. Serial No. 659,591. (No model.)

To all whom it may concern:

Be it known that we, MAURICE TALEN and GEORGE H. CROFT, of Geneseo, in the county of Henry and State of Illinois, have invented 5 a new and Improved Ripping Attachment for Sewing-Machines, of which the following is a full, clear, and exact description.

Our device relates to an improvement in attachments which are connectible to sewing-machines and used for ripping seams and for similar uses.

It comprises certain novel features of construction, which will be hereinafter described and claimed.

Reference is to be had to the accompanying drawings, forming a part of this specification, in which similar characters of reference indicate corresponding parts in all the figures.

Figure 1 is a perspective view showing a portion of the sewing-machine and the location of our device thereon. Fig. 2 is a side elevation of the device. Fig. 3 is a sectional elevation taken through the frame near the pivot of the cutting-disk, and Fig. 4 is a top plan view of the attachment.

Our device is intended for attachment to the table of a sewing-machine at the point where the belt passes upward through the table. It is attached to the table by means of a clamping-bar B, which has a horizontal arm B' secured to the base of the attachment, the body extending downward through the belt-hole and being secured to the under side of the table by means of a set-screw b.

The base A of the attachment is formed of a plate of metal, having an arm A' extending upwardly from one side thereof, and at the same side a flange A³, extending upwardly and then turning inwardly, forming a guide 40 to receive the sliding plate D and to securely hold the clamping-bar B. The clamping-bar B may, if desired, be made as a part of the base A, but is preferably made as a separate piece, as it would otherwise necessitate the 45 base being made of heavier metal than is desirable.

Upon the side of the base opposite the flange A³ and the arm A' is an upwardly-extending flange or web A², which is provided with a 50 horizontal slot a'. Upon the upper end of the arm A' is journaled a roller C, which is adapted to engage the sewing-machine belt.

The plate D is provided with a base D', formed by a flange at right angles to the body of the plate and engaging the under surface of the flange A³ upon the base. This plate is adjustably secured against the inner surface of the flange A² by means of the clamping-bolt a, which passes through the slot a' and is threaded into a hole in the plate D. This 60 plate extends upwardly and has a pulley C' journaled upon the same.

The cutting-disk E is secured to the side of the pulley C' or otherwise attached upon the same axis. This pulley C' is above the pulley 65 C, and the plate carrying the same may be adjusted so as to vary the relative angular position of the pulleys.

The upper edge of the plate D is curved sidewise, so as to form a guard D² for the cutting-disk E. At one edge the plate is recessed, as shown at d, exposing a section of the cutting-disk. Upon this edge of the plate and beneath the recess d the edge of the plate is formed at one side with a flange D³, which 75 is provided with a slot d', embracing the edge of the cutting-disk and forming a guide or guard for the reception of the material. This edge of the plate is extended downward, forming a leg D⁴, which engages the top surface 80 of the sewing-machine table.

In using our device the clamping-bar is inserted in the hole in the table through which the sewing-machine belt passes, and it is secured in place therein. The belt F is then 85 placed between the pulleys C and C'. This furnishes a sufficient contact upon the pulley C' to rotate the disk E. As the disk rotates the seam to be ripped is presented to the edge of the disk, when the threads will be promptly 90 cut. The cutting edge of the disk is protected by the guard-flange D², so that there is no probability of injury to the operator.

The relative angular position of the two pulleys may be varied by shifting the plate 95 D upon the base. As it is thrown toward the left in Fig. 2 it will cause a greater bend to be made in the belt, which will insure a larger arc of contact and at the same time increase the tension of the belt, thus furnishing an increased driving power when needed. The leg 100 D⁴, engaging the table-top, will furnish a firm bearing for this end of the plate.

The device is simple and cheap in construc-

tion and may be readily attached to or detached from any ordinary sewing-machine. By its means seams may be rapidly ripped without danger to the operator or of cutting 5 the cloth.

Having thus fully described our invention, we claim as new and desire to secure by Letters Patent—

1. A ripping attachment for sewing-machines, comprising a base - plate separate from and attachable to the sewing-machine table, and having two pulleys supported therefrom and adapted to receive the sewing-machine belt between them, and a ripping-disk connected with one of said pulleys, substantially as described. 15

2. A ripping attachment for sewing-machines, comprising a base - plate separate from and attachable to the machine-table, 20 and having two pulleys supported therefrom at different elevations and adapted to receive the belt between them by deflecting the belt, one of said pulleys being movable horizontally, and a cutting-disk connected to one of the pulleys, substantially as described. 25

3. A ripping attachment for sewing-machines, comprising a base - plate separate from and attachable to the machine-table and having a pulley mounted thereon, a plate adjustable horizontally upon the base-plate and having a pulley mounted thereon above the other pulley, and a cutting-disk connected to one of the pulleys, substantially as described. 30

4. A ripping attachment for sewing-machines, comprising a base attachable to the machine-table and having a pulley mounted thereon, a plate adjustable horizontally upon the base and having a pulley mounted thereon above the other pulley, said plate having its 35 upper portion curved over to form a shield for the edge of the cutting-disk, and a cutting-disk mounted upon the shaft of the second pulley, substantially as described.

5. A ripping attachment for sewing-machines, comprising a base attachable to the machine-table and having a pulley mounted thereon, a plate adjustable upon the base and having a pulley mounted thereon above the other pulley, said plate having its upper portion curved over to form a shield for the edge of the cutting-disk, and its front edge bent laterally and slotted to embrace the disk and form a work support or guide, substantially as described. 45

6. A ripping attachment for sewing-machines, comprising a base having an upwardly-extending arm on one side carrying a roller thereon, the same edge of the base-plate being curved upwardly and inwardly to 50 form a guide-flange, and an upwardly-extending flange or web upon the other side having a horizontally-extending slot therein, means for securing the base to the table, a plate lying alongside of the slotted web of the base 55 and having a base-flange engaging beneath the guide-flange of the base, a pulley and con-

nected cutting-disk journaled on said plate above the other pulley, said plate also having its upper edge rolled over the edge of the disk to form a guard therefor, and a recess at one 70 side exposing a section of the disk, substantially as described.

7. A ripping attachment for sewing-machines, comprising a base having an upwardly-extending arm on one side carrying a 75 roller, the same edge of the base-plate being curved upwardly and inwardly to form a guide - flange, and an upwardly - extending flange or web upon the other side having a horizontally - extending slot therein, means 80 for securing the base to the table, a plate lying alongside of the slotted web of the base and having a base-flange engaging beneath the guide-flange of the base and a leg engaging the machine-table beyond the belt, a pulley and connected cutting-disk journaled on said plate above the other pulley, said plate having a recess at one side exposing a section of the disk, and a bolt passing through the slot in the base-plate and entering the sliding 85 plate whereby the two may be adjusted, substantially as described.

8. A ripping attachment for sewing-machines, comprising a base having an upwardly-extending arm on one side carrying a 90 roller, said base being bent upwardly and inwardly to form a guide on the same side of the base, and an upwardly-extending flange or web upon the other side having a horizontally-extending slot therein, a clamping-arm 100 extending downward from said base and adapted to pass through the bolt-hole in the machine-table, a plate lying alongside of the slotted web of the base and having a base-flange engaging beneath the guide-flange of 105 the base, and a leg engaging the machine-table beyond the belt, a bolt passing through the slot in the base-plate and into the sliding plate, a pulley and connected cutting-disk journaled in said plate above the other pulley, said plate also having its upper edge 110 rolled over the edge of the disk to form a guard therefor, a recess at one side exposing a section of the disk, and a side extending flange at the lower part of the said recess, 115 said flange being slotted to embrace the disk and forming a work guide or support, substantially as described.

9. The combination in a ripping device, of a base-plate, two pulleys mounted to rotate 120 thereon and adapted to receive a belt between them, and a cutting-disk connected with one of said pulleys, with a sewing-machine having a table-top, means for securing the base-plate thereto with its pulleys in line with the 125 belt, the belt - pulleys, and their operating means, substantially as described.
